(57) **CLAIM**

The ornamental design for a stand-up food tray, as shown and described.

DESCRIPTION

FIG. 1 is a perspective view of a stand-up food tray showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an alternate left side elevation view thereof, rotated 90 degrees;

FIG. 7 is a top plan view thereof;

FIG. 8 is a bottom plan view thereof; and,

FIG. 9 is another perspective view shown in environmental use.

The broken lines are shown for illustrative purposes only and form no part of the claimed design.
